UNITED STATES PATENT OFFICE

LÉON V. SOLON, OF NEW YORK, N. Y.

DESIGN FOR A BATHTUB

Application filed October 6, 1930. Serial No. 37,149. Term of patent 7 years.

To all whom it may concern:

Be it known that I, LÉON V. SOLON, a citizen of the United States of America, residing at New York city, in the county and State of New York, have invented a new, original, and ornamental Design for Bathtubs, of which the following is a specification, reference being had to the accompanying drawing, forming part hereof.

The essential feature of my design consists in the general outline of the tub, which com-

prises a front side recessed slightly from the front and top of the tub,—thereby treating the front side as a panel separate and distinct from the rest of the tub.

Figure 1 is a perspective view of the bathtub showing my new design, and

Fig. 2 is a cross section thereof.

I claim:

The ornamental design for a bathtub substantially as shown and described.

LÉON V. SOLON.
